UNITED STATES PATENT OFFICE.

ABRAHAM B. LANDIS, OF WAYNESBORO, PENNSYLVANIA.

GRINDING-MACHINE.

1,016,751.

Specification of Letters Patent.

Patented Feb. 6, 1912.

Application filed April 25, 1902. Serial No. 104,687.

To all whom it may concern:

Be it known that I, ABRAHAM B. LANDIS, a citizen of the United States, residing at Waynesboro, in the county of Franklin and State of Pennsylvania, have invented certain new and useful Improvements in Grinding-Machines, of which the following is a specification.

The object of my said invention is to provide a grinding machine in which the motor for driving the grinding wheel is mounted and to provide an independent and uniform driving power for said grinding wheel at all angles, and it consists in various improvements in the construction and arrangement of parts whereby these objects are accomplished, all as will be hereinafter more fully described and claimed.

Referring to the accompanying drawings, which are made a part hereof, and on which similar reference characters indicate similar parts: Figure 1 is an elevation of one side of a grinding machine embodying my said invention, a portion of the headstock base and frame being broken away to show the interior construction, and Fig. 2 an end elevation, a portion of the carriage and supporting frame upon which it is mounted being shown in section for the purpose of showing its peculiar construction.

In said drawings the portions marked A represent the main frame or base of the machine; B the longitudinal traveling carriage; C the transverse movable "slider" mounted thereon; D the wheel base swiveled on said "slider"; E the motor mounted on said wheel base; F the headstock; and G the motor for driving the mechanism except the grinding wheel.

The main frame A is substantially of the same form and construction as shown in a number of my former patents. On one side it is formed with ways a' and a'' to support the carriage B, and is formed with a trough or gutter a^3 in its center, with an inclined surface leading thereto, to receive and conduct away the drippings and waste water. The carriage B is also of the usual construction, substantially as shown in my former patents, except that its top is formed gutter-shaped in cross section, with an aperture b at the bottom of said gutter which is immediately above the gutter a^3 in the frame A below. A guard b' is attached to the rear edge of the frame A at its top, and extends over a portion of the table B, covering the

way a^2 , on which this edge of the table travels. Said guard extends from end to end of the machine, and thus covers the way when the carriage shall be moved back and forth and is inclined or curved downwardly at its inner edge to shed any water or other material into the gutter b^3 from which it may run through holes b^5 onto the inclined surface of the top of the frame A from whence it will pass into the gutter a^3 , in the top of said frame A, thus completely protecting said way. A similar guard b^2 is mounted at one edge in a groove b^4 in the frame just beneath the inner edge of table A', and projects inwardly and downwardly over the adjacent edge of carriage B covering the way a' on which this edge of the carriage travels, and furnishing a downwardly inclined surface which will shed the water and dirt onto the inclined surface of the top of the carriage from whence it will pass through the aperture b into the gutter a^3 in the top of the table. By means of these guards the ways on which the carriage travels are kept clean and free from grit and dirt at all times. The "slider" C, and wheel base D, are also of the usual construction and arrangement. The grinding wheel W is mounted on the mandrel d in the usual manner.

The motor E may be any ordinary electric motor, connected by the incoming and outgoing line wires w and w' , with any source of power. Said motor is provided with a pulley e on its shaft, which is connected by a belt e' with a pulley d' on the mandrel d of the grinding wheel. The motor being rigidly secured to the wheel base is necessarily adjusted therewith, and thus furnishes a uniform driving power at all times and in all positions. The headstock F is journaled in a sleeve F', which sleeve is swiveled on the top of the base F², which is mounted on the top of the table A', as shown in Fig. 1.

The headstock F, motor G, and mechanism for connecting them form the subject-matter of a separate application, but will be briefly described herein to enable the construction and operation of the complete machine to be better understood.

The motor G is an ordinary electric motor of suitable power, mounted on a suitable bracket or frame A², attached on one end of the main frame A of the machine. It is connected by means of the belt g and suit-

able pulleys to the counter shaft 1, journaled in suitable bearings in said frame A², beneath the motor. A gear wheel 2 mounted on said contour shaft meshes with a smaller gear wheel 3 on the lower end of the vertical shaft 4 which is journaled in suitable bearings alongside said motor. Said shaft 4 is formed with a joint 5 extending in one direction, and a joint 6 extending in the other direction, and between said joints is formed in two parts adapted to telescope one within the other, being held from independent motion or rotation by being formed angular in cross section, or by a spline and groove connection. By this arrangement the table A', on which rest the headstock F and footstock F³, is permitted to swing to any angle for the purpose of grinding tapers on centers, etc., as will be readily understood. On the upper end of the upper portion of said shaft is mounted a gear wheel 7, which meshes with a gear wheel 8 on the end of the horizontal shaft 9, which is journaled in bearings on a bracket on the end of the table A' and in bearings formed in the base F² on the headstock, through which bearings said shaft is adapted to slide. A gear wheel 10 is mounted on shaft 9 within said base F² by a spline or similar connection, being thus adapted to slide thereon. A gear wheel 11 on the lower end of the shaft 7 meshes with said gear wheel 10, and a similar gear wheel 12 on said shaft 7 meshes with the gear wheel 13 on the short shaft 14, which extends through the frame to within the disk or face plate F carrying the center. The pinion 15 on the end of the shaft 14 meshes with an interior gear within said face plate, thus gearing said holding center to the motor G, by which it is driven.

The driving shaft 16, from which the mechanism for operating the carriage is driven in the usual manner, and as shown in my former patents, extends through bearings 45 in the frame A², and is geared to the counter shaft 1 through suitable gear wheels, preferably of the construction which permits a change of speed to be effected, as shown.

In a machine of this construction, the 50 grinding wheel being driven by an independ-

ent motor mounted upon the same base with said grinding wheel, its driving mechanism may be of very simple construction, while it is permitted to be operated at various angles and adjusted positions, doing away with 55 overhead gearing as in the ordinary construction, as will be readily understood. The arrangement for driving the work through the headstock F and the carriage driving shaft 16 from the same motor, also 60 makes a simple construction, and one adapted for "universal" grinding, giving the various required speeds of work and travel of grinding wheel by a constant speed motor. A very simple and compact machine is 65 thus provided, and one which may be readily adapted for a large variety of work.

Having thus fully described my said invention, what I claim as new and desire to 70 secure by Letters Patent, is:

1. In a grinding machine, the combination of the bed, the work holding and driving mechanism, a longitudinally movable carriage mounted on said bed, an electric motor mounted on the bed and connected to 75 drive the work and traverse the carriage, a slider mounted to move transversely upon said carriage, a grinding wheel base swiveled on said slider, another electric motor mounted upon said grinding wheel base, the grinding wheel with its spindle journaled in bearings in said base, and gearing connecting the shaft of said motor with said grinding wheel spindle, substantially as set forth.

2. In a grinding machine, the bed having 85 longitudinal ways, a carriage mounted upon said ways, a grinding wheel mounted upon said carriage, said ways covered by inwardly projecting shields, said carriage having a water channel in its top and outlets from 90 said channel communicating to a channel in said bed, substantially as set forth.

In witness whereof, I have hereunto set my hand and seal at Waynesboro, Pennsylvania, this 21st day of March, A. D. nine- 95 teen hundred and two.

ABRAHAM B. LANDIS. [L. S.]
